(57) **CLAIM**

The ornamental design for a shoe mop, as shown and described.

DESCRIPTION

FIG. 1 is a front elevational view of the shoe mop of the present invention;

FIG. 2 is a rear elevational view of the shoe mop of FIG. 1;
FIG. 3 is a left side elevational view of the shoe mop of FIG. 1, the right view being a mirror image thereof;

FIG. 4 is a top plan view of the shoe mop of FIG. 1;
FIG. 5 is a bottom plan view of the shoe mop of FIG. 1;
FIG. 6 is a front elevational view of an alternate embodiment of FIG. 1 (slip-on);

FIG. 7 is a rear elevational view of FIG. 6;
FIG. 8 is a left side elevational view of FIG. 6, the right being a mirror image thereof;

FIG. 9 is a top plan view of FIG. 6; and,
FIG. 10 is a bottom plan view of FIG. 6.
